US0D1107397S

(12) **United States Design Patent** (10) **Patent No.:** **US D1,107,397 S**
(45) **Date of Patent:** **** Dec. 30, 2025**

(54) **FOOTWEAR SOLE**

(71) Applicant: **Ariat International, Inc.**, San Leandro, CA (US)

(72) Inventors: **Jake Lawrence Rivas**, Oakland, CA (US); **Nicholas Sathia Fenselau**, Sunnyvale, CA (US); **Jose Rafael Monroy**, Milpitas, CA (US)

(73) Assignee: **Ariat International, Inc.**, San Leandro, CA (US)

(**) Term: **15 Years**

(21) Appl. No.: **29/876,264**

(22) Filed: **May 18, 2023**

(51) LOC (15) Cl. **02-04**

(52) U.S. Cl.

USPC **D2/947; D2/964**

(58) **Field of Classification Search**

(57) **CLAIM**

The ornamental design for a footwear sole, as shown and described.

DESCRIPTION

FIG. 1 is a front top isometric view of a footwear sole showing the design;

FIG. 2 is a rear bottom isometric view thereof;

FIG. 3 is a rear top isometric view thereof;

FIG. 4 is a front bottom isometric view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The dashed lines shown in the drawings illustrate portions of the footwear sole that are not presently claimed and thus form no part of the claimed design.

1 Claim, 10 Drawing Sheets
